UNITED STATES PATENT OFFICE.

VICTOR M. SUMMA, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

RAILWAY-CAR END CONSTRUCTION.

1,078,222.

Specification of Letters Patent. Patented Nov. 11, 1913.

Application filed January 14, 1913. Serial No. 741,997.

To all whom it may concern:

Be it known that I, VICTOR M. SUMMA, a citizen of the United States, residing at St. Louis, Missouri, have invented a certain 5 new and useful Improvement in Railway- Car End Construction, of which the following is a full, clear, and exact description, such as will enable others skilled in the art to which it appertains to make and use the 10 same, reference being had to the accompanying drawings, forming part of this specification, in which—

Figure 1 is an elevational view of a car end of my improved construction. Fig. 2 15 is a horizontal section taken on the line 2—2 of Fig. 1.

My invention relates generally to railway car end construction, and more particularly to the construction of the car end wall or 20 plate.

The principal object of my invention is to construct the car end wall in a single piece, preferably, a section of sheet metal, and to reinforce and stiffen the same by 25 means of ribs or corrugations, thus providing an extremely simple, inexpensive construction which will materially increase the strength and rigidity of the end portion of the car body.

30 A further object of my invention is to construct a car end wall or plate from a single sheet of metal, the same being particularly designed to effectively resist all stresses and strains resulting from shifting loads, ordinary service shocks and vibrations, or collisions.

35 A further object of my invention is to provide a comparatively strong, lightweight, one-piece car end plate or wall having great strength and rigidity, the use of 40 which materially reduces the initial cost of construction and cost of repairs.

In railway cars, and particularly those 45 designed for and used in freight service, the end portions of the car bodies and particularly the end walls and plates are subjected to great strains and stresses, not only because of the sudden starting and stopping of the cars and the consequent vibration, but 50 by reason of the shifting of the load or contents of the cars while the latter are in transit.

I propose to construct a car end in the 55 form of a corrugated sheet metal plate, the corrugations being arranged so as to

strengthen and stiffen the plate to a maximum degree, and to transmit to the sills and plates of the car body frame all stresses and strains which the end wall or plate may receive while in service. 60

To the above purposes my invention consists in certain novel features of construction and arrangement of parts hereinafter more fully described and claimed.

In the construction of my improved car 65 end, and as shown in the drawings, 10 designates a plate of sheet metal of such size and contour as to form the entire end wall of the car body, said plate having pressed therein a series of radially disposed corrugations 11 which start near the center of the plate and gradually become wider and deeper toward the edges thereof. The plate is preferably dished or made generally concavo-convex in cross section with the central portion thereof occupying a vertical plane slightly in front of the vertical plane occupied by the edges of 70 said plate. This dished formation, combined with the radially disposed corrugations 75 formed in the metal of the plate, provides an exceptionally strong and rigid structure which is effective in resisting externally applied crushing strains or stresses such as may be received in collisions, or internally applied stresses resulting from 80 shifting loads.

The edges 12 of the plate 10 are bent at right angles to the main body portion of the plate, thereby providing means whereby 90 the end wall or plate may be readily attached to the car underframe and car body frame.

By constructing the end wall or plate in a single piece, much time and labor can be 95 saved in initial cost and in the cost of repairs, and by radially corrugating the plate, the car end is materially strengthened and the impact and stresses produced by blows which the end plate may receive in service, 100 are transmitted to the strongest parts of the car body, namely the corners thereof.

If desired a suitable end door or window opening may be formed in the upper portion of the plate, as shown by dotted lines in 105 Fig. 1.

It will be readily understood that minor changes in the size, form and construction of the various parts of my improved car end may be made and substituted for those 110

herein shown and described without departing from the spirit of my invention, the scope of which is set forth in the appended claims.

5. I claim:

1. A car part comprising a sheet metal plate having radially arranged corrugations which become gradually wider toward the edges of said plate.

10. 2. A car part comprising a sheet metal plate having radially arranged corrugations which become gradually wider and deeper toward the edges of said plate.

15. 3. A car part comprising a sheet metal plate having radially arranged corrugations which start adjacent to the center of the plate and become gradually wider and deeper toward the edges of said plate.

20. 4. A car body part comprising a dished sheet metal plate having radially arranged corrugations.

25. 5. As a new article of manufacture, a car end comprising a metal plate having radially arranged corrugations which become gradually deeper toward the edges of said plate.

30. 6. As a new article of manufacture, a car end formed of a single piece of sheet metal provided with radially arranged corrugations which become gradually wider toward the edges of said piece of sheet metal.

35. 7. As a new article of manufacture, a car end, formed of a single piece of sheet metal provided with radially arranged corrugations which gradually increase in depth and width toward the outer edges of the plate.

40. 8. A car end comprising a sheet metal plate the entire body of which is provided with straight corrugations extending from points adjacent to the center of the plate toward the edges of said plate and which corrugations gradually increase in depth toward the edges of said plate.

45. 9. A car end comprising a sheet metal plate having straight corrugations extending from points adjacent to the center of the plate toward the edges of said plate, which corrugations gradually increase in width and in depth toward the edges of the plate.

10. A car end formed of sheet metal and having formed therein a series of substantially straight stiffening ribs or corrugations which are arranged at angles with respect to the marginal edges of said car end and which ribs or corrugations gradually decrease in width and depth toward a common starting point on the sheet of metal. 55

11. A car end formed of sheet metal and having formed therein a series of substantially straight stiffening ribs or corrugations which are arranged at angles with respect to the marginal edges of said car end, and which stiffening ribs or corrugations 60 gradually increase in depth and width toward the marginal edges. 65

12. A car end comprising a dished metal plate having formed therein a series of stiffening ribs or corrugations which are arranged at angles relative to each other and to the marginal edges of said car end. 70

13. A car end comprising a metal plate the entire body of which has pressed therein a series of comparatively straight stiffening 75 ribs or corrugations which taper in width and depth lengthwise.

14. A car end comprising a metal plate the entire body of which has pressed therein a series of comparatively straight stiffening 80 ribs or corrugations which gradually increase in width and depth toward the marginal edges of said car end.

15. A car end comprising a dished sheet metal plate having pressed therein a series 85 of substantially straight stiffening ribs or corrugations which taper in width and depth lengthwise.

16. A car end comprising a dished sheet metal plate having pressed therein a series 90 of substantially straight stiffening ribs or corrugations which gradually increase in depth and width toward the marginal edges of said car end.

In testimony whereof I hereunto affix my 95 signature in the presence of two witnesses, this eighth day of January, 1913.

VICTOR M. SUMMA.
